(57) **CLAIM**

The ornamental design for a power brush, as shown and described.

DESCRIPTION

FIG. 1 is a perspective view of my new design for a power brush.

FIG. 2 is a front side elevational view of my new design.

FIG. 3 is a back side elevational view thereof.

FIG. 4 is a top plan view thereof.

FIG. 5 is a bottom plan view thereof.

FIG. 6 is a left end elevational view of the design shown in FIG. 1; and,

FIG. 7 is a right end elevational view of the design shown in FIG. 1.

The bristles, which are partially shown for ease of illustration, are understood to be hemispherical in form.

1 Claim, 4 Drawing Sheets

FIG. 1

FIG. 7
